INSECTICIDE AND FUNGICIDE

William E. Bradley, Los Angeles, Calif., assignor
to Union Oil Company of California, Los Angeles, Calif., a corporation of California

No Drawing. Application June 8, 1942,
Serial No. 446,273

7 Claims. (CL 167—28)

1

This invention relates to the production of improved fungicides and insecticides containing synthetic light oils.

In the past it has been common practice to employ naturally occurring petroleum fractions, especially those fractions boiling in the range of 350° F. to 800° F. in the preparation of insecticides and fungicides. These oils have been used alone or commingled with auxiliary additives designed to produce specific toxic, spreading or emulsifying qualities. For example, typical fly sprays have comprised highly refined kerosene fractions, specific toxic ingredients such as pyrethrum extract, and perfumes. Typical spray oils or fungicide oils have comprised simply highly refined petroleum fractions boiling in the light lubricating oil range. "Soluble oil" sprays commonly comprised petroleum fractions, soaps, alcohols and water. In all such preparations it is obviously desirable that the product shall have a controlling effect on the insect pest or undesirable fungus and yet be as harmless as possible to human beings, domestic animals, plants and to equipment used in the application. For indoor operation, such as fly spray, it is further desirable that the oil base have an odor which is very bland or rather pleasing. It is known that many of the insecticidal and fungicidal oils now in use are somewhat toxic to human beings, domestic animals and plants. Furthermore they have a serious destructive action on equipment due to their tendency to dissolve or swell rubber parts used in the equipment. Finally the odors of some sulfur- and nitrogen-containing bodies frequently associated with petroleum fractions, and even the odors of some of the hydrocarbons themselves, are objectionable. Many petroleum fractions which have been used in fungicides or insecticides have been heavily treated with strong sulfuric acid or liquid sulfur dioxide for example, in order to remedy to some extent the above undesirable properties.

It is the object of this invention to provide insecticides and fungicides compounded from synthetic oils having insecticidal and fungicidal properties equivalent to those of the petroleum products now in use, but having other properties in marked contrast to those of the petroleum products, namely, (1) a less pronounced and more pleasing odor, (2) relatively low swelling action on natural or synthetic rubbers, (3) relatively low toxicity to human beings, animals, and plants, (4) relative freedom from sulfur- and nitrogen-containing impurities, and (5) sufficient purity and stability as to require only moderate finishing

2

treatment with acid, clay, sulfur dioxide or caustic.

According to this invention, substantially pure isoparaffinic products boiling in the range 350° F. to 800° F. are prepared by any process involving principally alkylation of paraffins with mono-olefins. The product is then subjected to fractionation and finishing treatment, in either order, and compounded with the desired additives, such as toxic, spreading, or emulsifying agents, anti-oxidants, etc. The fractionation is preferably carried out continuously, in a vacuum, or using steam. Generally the insecticide base oils such as fly spray base, are fractionally distilled so as to boil within the range of about 350° F. to 550° F., while the spray oils such as those used in fungicides, are fractionated so as to boil in the range of about 450° F. to 800° F. The finishing treatment may involve treatment with concentrated or fuming sulfuric acid in the proportions of about one pound H_2SO_4 per gallon, or in smaller proportions, followed by water washing, caustic washing and/or distillation. Other conventional finishing treatments may also be used, such as clay treatment, with or without a preceding sulfuric acid treatment; or vapor phase treatment with fuller's earth, clay, partly hydrated zinc chloride, etc.

As a specific example of my invention, an isoparaffinic fly spray base was prepared, using as a starting material a sample of "heavy alkylate" obtained as a bottoms fraction from distillation of the alkylated product from a commercial alkylation plant. The latter was a conventional plant for continuously reacting isobutane with butenes and pentenes, employing H_2SO_4 as a catalyst, and was similar to that described in the Refiner, vol. 20, 1941, page 379. The reaction mixture in this instance comprised about 45 volumes of isobutane and about 100 volumes of approximately 92% sulfuric acid to each volume of olefins. The debutanized alkylated product from this plant was distilled to obtain a light alkylate suitable for use in aviation gasoline and a heavy alkylate bottoms fraction which, in this case, had a boiling range of approximately 350 to 600° F. and consisted of substantially pure isoparaffins. A portion of this material was steam distilled to obtain a fraction having a boiling range of approximately 380 to 480° F. This fraction was agitated one minute with 98% H_2SO_4 in the ratio of 10 pounds acid per barrel of oil and settled for one hour. The oil was then decanted from the acid sludge, washed successively with an equal volume of water and 10% by volume of 2% caustic

soda solution, and steam distilled, taking about 95% overhead. This overhead fraction, which tested over 95% isoparaffins, was washed with 5% by volume of 2% caustic soda solution, and compared with a typical high quality kerosene type fly spray base made in the following manner:

A kerosene fraction of 380 to 480° F. boiling range distilled from crude oil was subjected to extraction with an equal volume of liquid sulfur dioxide at a temperature of about 15° F. The "raffinate" fraction, which contained smaller proportions of aromatic type hydrocarbons, sulfur- and nitrogen-containing materials than either the "extract" fraction or the feed stock, was freed of sulfur dioxide and treated with 10 pounds of 98% H_2SO_4 per barrel followed by washing with an equal volume of water and 10% of 2% caustic soda solution successively, as described above. The characteristics of the two products follow:

	Synthetic isoparaffinic	Acid treated kerosene raffinate fraction
Spec. gravity at 60°/60° F.	.787	.806.
Sulfur content, per cent by wt.	0.03	0.15.
Engler dist'n, °F.:		
10%	404.	386.
50%	420.	417.
90%	452.	454.
Approx. viscosity, S. U. at 100° F., sec.	30.	30.
Pour point, °F.	Below -90.	About -45.
Equal vol. aniline point, °F.	198.	160.
Insecticidal value.	Good.	Good.
Lack of phytocidal effects.	Excellent.	Do.
Swelling action on rubber, per cent.	10%.	50% to 100%.
Odor	Excellent.	Good.

Finished insecticide sprays were prepared from the above two materials by adding to each 0.2% of pyrethrins as a lethal ingredient and a small amount of perfume. The two products were equally effective insecticides.

The yield of heavy alkylate in the process described above may be improved by (1) operating at relatively low ratios of isobutane to olefin in the feed stock and recycle stream, (2) alkylating at relatively high temperatures, particularly above 50° F., and (3) using H_2SO_4 of rather low strength, in the neighborhood of 90% or below.

An isoparaffinic spray oil was prepared as follows: Five volumes of "heavy alkylate," as described above, and five volumes of 98% H_2SO_4 were introduced into a vessel equipped with an agitating device. While agitating this mixture at a temperature of about 60° F. one volume of crude di-isobutylene was added in small proportions over a period of one-half hour. After an additional three hours of agitation the mixture was allowed to settle and the hydrocarbon phase was decanted from the acid phase. The hydrocarbon phase was washed with 10% by volume of 2% caustic soda solution and steam distilled to remove that fraction boiling below 480° F. The high boiling residue was treated with 10 pounds of 98% H_2SO_4 per barrel followed by water and caustic, as described above, and steam distilled to obtain a distillate having a final boiling point of about 620° F. This product was compared with a typical high quality spray oil made from a petroleum fraction as follows:

A fraction from crude oil distillation having a boiling range of about 480 to 620° F. was treated with 125% by volume of liquid sulfur dioxide in four counter-current stages at a temperature of about 50° F. The raffinate fraction after removal of all sulfur dioxide was agitated one-half hour with sulfuric acid in the ratio of 50 pounds of 103% H_2SO_4 per barrel of oil. After two hours

of settling, the acid sludge phase was drawn off and the oil was agitated one-half hour with a fresh charge of 50 pounds of Death Valley clay per barrel. After one hour of settling the bulk of the clay was drawn off and the finished oil was decanted from the remainder. Results of comparative tests of the two spray oils follow:

	Synthetic isoparaffinic	Typical spray oil
Specific gravity at 60° F./60° F.	.835.....	.881.....
Engler dist'n, °F.:		
10%	545.....	558.....
50%	552.....	600.....
90%	571.....	630.....
Sulfur, per cent by wt.	0.03.....	0.20.....
S. U. viscosity at 100° F., sec.	59.....	56.....
Pour point, °F.	-70.....	-55.....
Equal vol. an. pt., °F.	184.....	174.....
Swelling action on rubber, per cent.	5% to 10%.....	25% to 75%.....
Unsulfonated residue, de Ong, percent.	57.....	85.....
Lack of phytocidal effects.	Excellent.....	Good.....
Insecticidal value.	Good.....	Do.....
Fungicidal value.	do.....	Do.....

Of particular interest are the above values for percent unsulfonated residue which is generally considered to be a measure of the quality of the spray oil as being non-injurious to plants. The two spray oils described above were emulsified with water after addition of 0.5% of tetraethylene glycol monolaurate and it was found that the product containing the isoparaffinic material, in spite of its low de Ong value was relatively non-injurious to plants and foliage. Low specific gravity, low sulfur content, low pour point and high aniline point also distinguish the synthetic isoparaffinic oils of both this table and the earlier table from the typical petroleum products.

The relative toxicity to animals of the above described synthetic isoparaffinic oils, compared to the petroleum fractions may be deduced from data included in Report No. 80 of the Medical Research Council of the British Industrial Health Research Board, published as a book entitled "Toxicity of Industrial Organic Solvents" by His Majesty's Stationery Office, London in 1937. In the course of a discussion of the relative toxicities of various types of hydrocarbon mixtures it is stated that for mixtures containing principally cycloparaffins and acyclic paraffins, the toxicity increases with increasing cycloparaffin concentration, and also with increasing specific gravity. On this basis the isoparaffinic oils described above are definitely less toxic to animals and human beings than the petroleum products, for they not only have a lower specific gravity but are by definition paraffinic in nature, while the petroleum products are known to contain appreciable if not large amounts of cycloparaffinic compounds.

It may be desirable to add antioxidants to the synthetic isoparaffinic oils just as it is desirable in the case of very highly refined mineral oils in which naturally occurring antioxidants have been removed in the refining process. As examples of desirable antioxidants we may cite the various substituted aminophenols, hydroquinone, cresols, naphthols, etc.

The spray oils described above are generally used in the form of water emulsions with or without emulsifying agents and mutual solvents. Other oils which are likewise frequently used in emulsion form are textile oils and cutting oils. For these materials also, synthetic isoparaffinic products would be definitely superior to the petroleum fractions now in use because of their low toxicity to human beings and low swelling power for rubber.

While the character of certain materials has been described in detail in order to clarify the significance of the invention, it is not intended to impose limitations thereby. For example the alkylation process may involve other catalysts, such as HF or AlCl₃, etc., other olefins such as those produced from cracking, chlorination and dehydrochlorination, oxidation and dehydration, etc., other isoparaffinic feed stocks, and other apparatus or operating conditions. The emulsifying agents used with the isoparaffinic spray oils for emulsions, suspensions, or soluble oils may include not only tetraethylene glycol monolaurate but other esters, soaps, alcohols, etc., such as calcium caseinate, saponin, soaps of whale oil, fish oil, cottonseed oil, cocoanut oil, etc., and their fatty acids, fatty acids themselves, phenol homologs, Bordeaux mixture, and rosin. Some of these may also have other effects such as spreading, sticking, or toxic effects. Other auxiliary toxic agents may include nicotine sulfate, rotenone, etc. It will be apparent to those skilled in the art that numerous other modifications may be made without departing from the scope of the following claims.

I claim:

1. A process for the treatment of areas infested with fungus and insects, which comprises spraying said areas with a material comprising a substantially pure isoparaffinic oil boiling in the range of about 350° F. to about 800° F.
2. A process for the treatment of areas infest-

ed with insects, which comprises spraying said areas with a material comprising a substantially pure isoparaffinic oil boiling in the range of about 350° F. to about 550° F.

5 3. A process for the treatment of areas infested with fungus, which comprises spraying said areas with a material comprising a substantially pure isoparaffinic oil boiling in the range of about 450° F. to about 800° F.

4. An insecticide consisting essentially of small amounts of pyrethrins, dissolved in a substantially pure isoparaffinic base oil boiling within the range 350° F. to 550° F.

5 5. An insecticidal and fungicidal spray emulsion consisting essentially of a substantially pure isoparaffinic base oil boiling in the range 350° F. to 800° F., an emulsifying agent, and water.

6. An insecticide consisting essentially of small amounts of pyrethrins and a perfume, dissolved in a substantially pure isoparaffinic oil boiling in the range of approximately 350° F. to 550° F. and prepared by a process involving alkylation of an olefin and an isoparaffin.

25 7. An insecticidal and fungicidal spray emulsion consisting essentially of an emulsifying agent, water, and a substantially pure isoparaffinic oil boiling in the range of approximately 450° F. to 800° F. and prepared by a process involving alkylation of an olefin and an isoparaffin, said oil having a specific gravity of about 0.835 and a de Ong unsulfonated residue of about 57%.

WILLIAM E. BRADLEY.
